MIXING MACHINE

Samuel B. Beugler, Los Angeles, Calif.

Application May 13, 1955, Serial No. 508,115

3 Claims. (Cl. 259—72)

This invention relates to a mixing machine of the type employed in mixing paints by agitating or shaking containers thereof.

The primary object of the invention is to provide a machine of the above character which is rapid and thorough in its operation and in which the mixing action is effected by subjecting the container to a combined vertical or lateral swinging movement and a horizontal oscillatory movement in which the vertical swinging motion is accomplished on a pivotal axis located below the center of gravity of the container and its contents whereby the upper and lower end portions of the container will have different relative movements or lengths of paths of travel, and in which the horizontal movement comprises short oscillations around the vertical axis of the container during vertical or lateral swinging thereof.

Another object is to provide a mixing machine in which a lidded mixing container is clamped and rigidly supported in a fashion such as to insure against spilling of the container's content during the mixing operation, in which the container may easily and quickly be mounted in the machine and readily removed therefrom and in which the machine may be quickly adjusted for the reception and working of containers of several sizes.

A further object is to provide a mixing machine embodying a container mounting capable of combined rectilinear rocking movement on a vertical plane and oscillatory movement on a horizontal plane, in which such movements of the mounting are effected through the medium of a single revoluble crank, a crank arm actuated thereby, and combined horizontally and vertically pivoted supports for said mounting actuated through said crank arm.

With the foregoing objects in view together with such other objects and advantages as may subsequently appear, the invention resides in the parts and in the combination, construction and arrangement of parts herein-after described and claimed, and as illustrated by way of example in the accompanying drawings in which:

Fig. 1 is a perspective view of the mixing machine showing it fitted with a container;

Fig. 2 is a plan view of the machine with portions removed;

Fig. 3 is an end view with portions shown in section to clearly show the pivotal mountings;

Fig. 4 is a detail in horizontal section taken on the line 4—4 of Fig. 3;

Fig. 5 is a detail in horizontal section as seen on the line 5—5 of Fig. 3;

Fig. 6 is a view in section and plan taken on the line 6—6 of Fig. 3;

Fig. 7 is a view in vertical section partly in elevation and with parts broken away as seen on the line 7—7 of Fig. 3;

Fig. 8 is a detail in section and elevation taken on the line 8—8 of Fig. 7;

Fig. 9 is a detail in horizontal section taken on the line 9—9 of Fig. 3; and

2

Figs. 10 and 11 are diagrams depicting the movements of the mixing mechanism.

Referring to the drawings more specifically A indicates generally the frame of the machine which embodies a base portion B at its forward end carrying an upstanding pivot pin 14 on which is swivelled an upstanding yoke C comprising a horizontal cross bar 15 fitted at its ends with standards 16—16' spaced equidistant on opposite sides of the pivot 14.

10 The bar 15 normally extends crosswise of the machine and is mounted on the pivot 14 for short oscillatory movement as will presently appear.

Mounted on the upper ends of the standards 16—16' is an upright rectangular frame D embodying parallel side rails 17—17' and top and bottom end rails 18—18', the frame D being carried on aligned pivots a—a' mounted on the standards 16—16' and engaging the side rails 17—17' at opposed points located below the mean horizontal center of the frame D.

20 The upper end portion of the frame D is connected to the divergent end of a V-shaped crank arm E the side members b—b' of which extend astride the frame D and are connected at their ends c—c' to the side rails 17—17' adjacent their upper ends by aligned pivots d—d' as particularly shown in Figs. 3 and 4.

25 The convergent end e of the crank arm E is connected through a ball bearing f with a crank g mounted on a horizontal disk 18 fixed on the upper end portion of a vertical rotary shaft 19 fitted with a pulley 20 carrying a driving belt 21 passing around a pulley 22 on the drive shaft 23 of a motor F. The vertical axis of the shaft 19 extends on a plane extending through the vertical axis of the pivot 16 and on which plane lies the vertical center of the frame D.

30 35 Mounted for vertical adjustment on the frame D is a circular container supporting platform G having opposed slide-ways h—h' fixed on its margin which slidably engage guide ribs i—i' extending longitudinally of the inner faces of the side rails 17—17' of the frame D.

40 The slide-ways h—h' normally seat on the lower end rail 18' but are adapted to be latched at different elevated points on the side rails 17—17' as will be later described.

45 Slidably mounted in the upper portion of the frame D is a circular clamping disk H having slide-ways j—j' fixed on opposed marginal portions thereof which slidably engage the ribs i—i'. The disk H is swivelly connected to the lower end of a threaded stem 24 which extends vertically through the top rail 18 of the frame D in screw engagement therewith and is fitted at its upper end with a crank 25 whereby the stem 24 may be manually rotated to advance and retract the stem 24 and the disk H carried thereon.

50 55 The connection between the disk H and the stem 24 comprises an inverted socket 26 formed centrally of the disk and projecting from the upper face thereof, which socket consists of a cylinder k formed with an inturned end flange l encompassing the lower end portion of the stem 24 which latter is formed with a flange m on its lower end projecting beneath the flange l. Pins n carried by the cylinder k extend beneath the lower end of the stem 24 and form a bearing between the stem and the disk H.

60 65 The platform G and clamping disk H are designed to receive therebetween a closed ended cylindrical container J constituting a receptacle of materials to be mixed; the platform and disk having flanges o and p respectively engageable with the rims of the container ends.

70 While the construction herein set forth is adapted to be contrived for the reception of a container J of any practical size, the machine here shown is intended for use in the mixing of paint in the usual gallon, half gallon, and quart cans, and accordingly the platform G

3

and disk H are dimensioned to diametrically accommodate a gallon can with the end margins of which the inner peripheries of the flanges o and p conform, and the spacing between the platform G and the disk H is such as to accommodate such can there-between when the disk H is in its near uppermost position. In order to adapt the machine for the reception of cans of lesser diameters than the gallon can, the platform G and disk H are formed on their adjacent faces with opposed annular ribs q—q' respectively diametrically dimensioned to conform to the peripheries of the ends of half-gallon cans, and are also formed with opposed annular ribs r and r' dimensioned to conform to the ends of quart cans, the ribs q—r and q'—r' being concentric with the aligned axes of the platform and disk.

In order to adapt the machine to receive cans of lesser height than that of a gallon can, the platform G is adjustable to different heights on the frame D as before mentioned. In order to support the platform G in elevated positions the guide ribs i—i' are each formed with a pair of superimposed spaced notches s and t and the platform G is fitted with a pair of complementary spring pressed catches 26 presented toward the ribs i—i' for engagement with either of the notches s or t and thereby releasably hold the platform in its raised positions. One of the latches 26 is detailed in Fig. 9 as comprising a tubular housing u which is formed in continuation of the adjacent slideway h or h' and has an open end presented to the rib i or i'.

A bolt v slidable in the housing u is fitted with a stem w which projects from the inner end of the housing. A spring x wound on the stem bears against the bolt to normally hold it in an advanced position for engagement with the notches s—t. A laterally projecting handle y is mounted on the stem w whereby the bolt may be manually retracted to free it from engagement with the notch with which it is engaged.

In the operation of the invention a capped can J containing the material to be mixed, such as paint, is clamped between the platform G and the disk H by initially seating it on the platform beneath the then raised disk and then clamping the disk against the upper end of the can by manipulation of the stem 24. The can will then be securely held against displacement and the cap or lid thereof if unsecured to the can body tightly held in place.

To effect a mixing action on the contents of the can J the eccentric crank g is set in motion thereby rectilinearly reciprocating and laterally oscillating the crank arm E which by reason of the pivotal mounting of the frame D on the pivots a—a' causes the frame D to swing forward and back in a rectilinear path of travel a single reciprocation on each revolution of the crank g as indicated by the full and dotted lines in Fig. 11 and denoted by the double headed arrow M. At the same time the frame D is caused to oscillate horizontally by virtue of the pivotal mounting of the yoke C carrying the frame D afforded by the pivot 14. The relative reciprocal and oscillatory movements of the frame D and the can J carried thereon is diagramed in Fig. 10 and indicated by double headed arrows N and O respectively.

The solid lines here indicate diagrammatically the forwardmost position of the can J, frame D, crank arm members b—b' and eccentric crank g, dot and dash lines indicate their intermediate positions, while the dotted lines indicate their retracted positions.

By the employment of the diverging crank arm members b—b' leading from the crank g to opposite sides of the frame D the latter will be caused to oscillate horizontally on rotation of the crank g, since, when the crank g is in its forwardmost position on a plane extending through the shaft 19 and pivot 14 the frame D will be

disposed perpendicular to such plane, as indicated by the full lines in Fig. 10, then when the crank g is moved ninety degrees from its forwardmost position, the frame will be swung laterally on the pivot 14 to an angular position relative to its initial position as indicated by the broken lines D¹ and D² in Fig. 10. This oscillating movement of the frame D is of course imparted to the can J and its fluid contents thereby effecting a horizontal oscillating surging movement of the can's contents cross-wise of back and forth surging movement effected by rocking of the container.

It is to be noted that by pivoting the frame D below its horizontal center and supporting the can on the platform G either on the lower end of the frame or either 15 of the notches s—t, the major portion of the can will extend above the pivoted mounting of the frame and will therefore be caused to travel a greater distance than the lower portion thereof on the rectilinear rocking movement of the can. This movement is highly effective in 20 agitating the contents of the can particularly where the can is mounted in an inverted position on the platform G with previously settled solids therein now located in the upper portion of the can.

The recited movements of the can effect rapid and 25 thorough mixing of its contents without appreciable jar and without disturbing noise as is generally occasioned by powered mixing machines.

While a specific embodiment of the invention has been shown and described, the invention is not limited to the 30 exact details of construction set forth, and the invention embraces such changes, modifications and equivalents of the parts and their formation and arrangement as come within the purview of the appended claims.

I claim:

35 1. In a mixing machine, an upstanding rectangular frame having parallel side and end members, an upstanding yoke pivotally supported for horizontal swinging movement, pivots carried by said yoke connected to the side members of said frame below its horizontal center, 40 means connected to the upper portion of said frame adapted to collectively swing said frame vertically and oscillate said yoke horizontally, guide ribs on said side members extending longitudinally thereof, a container supporting platform, guide-ways on said platform slidably engaging said ribs, means for supporting said platform in various positions along said guide ribs, a disk 45 spaced above said platform, guide-ways on said disk slidably engaging said ribs, and screw means carried by said frame for clamping said disk on a container supported on said platform.

50 2. In a mixing machine, a rectangular frame having parallel side members, pivots supporting said frame for vertical swinging movement, guide-ribs on the inner faces of said side members extending longitudinally thereof, a 55 container supporting platform, guide-ways on said platform slidably engaging said ribs, notches in said ribs, catches on said guide-ways releasably engageable with said notches for holding said platform on said frame in various adjusted positions thereon, means for clamping a 60 container on said platform in any of its adjusted positions, and means connected to the upper portion of said frame for swinging it on said pivots.

65 3. The structure called for in claim 2 in which said notches and catches are arranged to support said platform with the major portion of a container thereon extending above the plane of said pivots.
